The ornamental design for a scanner device, as shown and described.

DESCRIPTION

FIG. 1 is a perspective view of a scanner device; FIG. 2 is another perspective view of the scanner device of FIG. 1;

FIG. 3 is a top plan view of the scanner device of FIG. 1; FIG. 4 is a bottom plan view of the scanner device of FIG. 1; FIG. 5 is a left-side elevation view of the scanner device of FIG. 1, the right-side elevation view being a mirror image of FIG. 5;

FIG. 6 is a front elevation view of the scanner device of FIG. 1; and,

FIG. 7 is a back elevation view of the scanner device of FIG. 1.

The broken lines are directed to unclaimed portions and form no part of the claimed design.

The region within the broken line boundary in FIG. 7 forms no part of the claimed design.
